United States Patent

Des. 241,031
Patented Aug. 17, 1976

241,031

SOLAR HOUSE

Harry E. Thomason and Harry Jack Lee Thomason, Jr.,
both of 6802 Walker Mill Road SE., Washington, D.C.
(District Heights, Md., branch), 20027

Filed Dec. 16, 1974, Ser. No. 533,212

Term of patent 14 years

Int. Cl. D25—03

U.S. Cl. D25—17

FIG. 1

FIG. 2

FIG. 3

FIG. 4

FIG. 1 is a view from the north, looking southward of a solar house.

FIG. 2 is a view from the south, looking northward.

FIG. 3 is a view from the east, looking westward.

FIG. 4 is a view from the west, looking eastward.

For convenience of illustration, only parts of the brick surfaces and roofing have been shown in the several views of the drawings. It is to be understood that these surfaces continue throughout the areas indicated.

We claim:

The ornamental design for a solar house, as shown and described.
